(57) **CLAIM**

The ornamental design for an inkjet cartridge, as shown and described.

DESCRIPTION

FIG. 1 is a front isometric view of an inkjet cartridge, showing my new design;

FIG. 2 is a rear isometric view of the inkjet cartridge of FIG. 1;

FIG. 3 is a front view of the inkjet cartridge of FIG. 1;

FIG. 4 is a rear view of the inkjet cartridge of FIG. 1;

FIG. 5 is a left side view of the inkjet cartridge of FIG. 1;

FIG. 6 is a right side view of the inkjet cartridge of FIG. 1;

FIG. 7 is a top view of the inkjet cartridge of FIG. 1; and,

FIG. 8 is a bottom view of the inkjet cartridge of FIG. 1.

The broken lines of FIGS. 1-4 and 8 are provided for purposes of illustration and form no part of the claimed design of the present application.

1 Claim, 6 Drawing Sheets

FIG. 1
